UNITED STATES PATENT OFFICE.

JULIA D. BROWN, OF NEW YORK, N. Y.

WATCH-HOOK

1,259,830.

Specification of Letters Patent. Patented Mar. 19, 1918.

Application filed November 16, 1917. Serial No. 202,300.

To all whom it may concern:

Be it known that I, JULIA D. BROWN, a citizen of the United States, borough of Manhattan, city, county, and State of New York, have invented certain new and useful Improvements in Watch-Hooks, of which the following is a specification.

My invention is an improved watch-hook. The object of my invention is to provide a watch-hook that can be readily attached to the swivel of a watch-chain or fob in order to support the watch in a belt or skirt; which in use will hold the watch in place and will prevent it from slipping down when, for instance, placed in the belt.

The invention, broadly speaking, consists of a piece of wire or other strip of metal bent into the shape of an inverted U, one branch of the inverted U having formed at its lower extremity a ring adapted to pass onto the swivel of a watch-chain or fob and the other being adapted to fit over a skirt or belt or through a button-hole or to be applied to some other portion of the garment.

In the accompanying drawings Figure 1 shows the device as applied to the swivel of a watch-chain or fob: Fig. 2 is a perspective view of the device in position, fitting over the top of a belt; Fig. 3 is a front elevation.

In each of these figures, 1 represents the inverted U member, 4 represents the ring formed in the lower extremity of the side 2 of the inverted U member and which is adapted to be applied to the swivel of a watch-chain or fob as shown in Fig. 1. In the preferred form of my device the ring 4 is bent outward in the plane of the inverted

U, as shown in Fig. 1, the plane of the ring remaining substantially perpendicular to the plane of the inverted U. This bending is in order that when it is in operative position on the swivel of the watch-chain or fob and is supporting the watch, the device may be in substantially a vertical position. The side 3 of the inverted U member is used to pass over the belt or top of the skirt or through a button-hole of the jacket to prevent the watch from slipping down. In Fig. 2 I have shown the device in use passing over a belt or the top of a skirt. The lower extremity 5 of the side 3 is blunt in order not to damage the garment.

Having thus described my invention what I claim is:

1. A watch-hook in the shape of an inverted U, the lower extremity of one of the arms of the inverted U being formed into a ring to receive the swivel of a watch-chain or fob, the said ring being bent outward in the plane of the inverted U, the plane of the ring remaining substantially at right angles to the plane of the inverted U.

2. A watch-hook in the shape of an inverted U, the lower extremity of one of the arms of the inverted U being formed into a ring to receive the swivel of a watch-chain or fob, the said ring being bent outward in the plane of the inverted U, the plane of the ring remaining substantially at right angles to the plane of the inverted U, and the lower extremity of the other arm being blunt.

In testimony whereof, I have signed my name to this specification.

JULIA D. BROWN.
